AUTOMATIC SWITCH

Reginald Taylor, Liverpool, England, and George Thomas Baker, Caerphilly, Wales, assignors to Associated Telephone and Telegraph Company, Chicago, Ill., a corporation of Delaware

Application October 31, 1935, Serial No. 47,538
In Great Britain November 23, 1934

8 Claims. (Cl. 179—18)

The present invention relates to automatic switches for use in telephone or like systems and is more particularly concerned with switches of the two-directional type arranged to be set as regards the first movement in response to impulses and thereafter to hunt for an idle line in the group selected. The invention moreover contemplates the use of switches of the so-called large capacity type in which hunting takes place 5 simultaneously over a plurality of sets of wipers and it is desirable to ensure that if a plurality of wipers engage idle lines simultaneously there shall be a definite order of priority in which they are taken into use.

15 According to one feature of the invention in an automatic switch arranged to hunt for an idle line, a relay controlling the drive circuit for the magnet effecting the hunting operation is energized during the said operation and by its de- 20 energization opens the magnet circuit and applies guarding potential to the selected line.

According to another feature of the invention in an automatic switch arranged to test simultaneously over a plurality of test wipers for an 25 idle line, the test relays associated respectively with the various test wipers are arranged to be all energized during the hunting operation while when any test wiper encounters an idle line its test relay is de-energized and the drive circuit 30 for the operating magnet broken thereby.

A further feature of the invention is that in an automatic switch provided with two sets of wipers and arranged to perform a hunting operation during which testing for an idle line takes place 35 over both sets of wipers simultaneously, during the hunting operation both the test relays associated with the respective test wipers are energized each relay being arranged to release when its associated wiper encounters an idle line, while if 40 both relays release due to two idle lines being encountered simultaneously a circuit is subsequently completed for one particular relay only so that one set of wipers is always given definite preference.

45 Another feature of the invention is that in an automatic switch arranged to be set by impulses to select a particular group of lines and thereafter to hunt automatically for an idle line in the selected group, a relay energized when the switch 50 is taken into use serves to operate the test relay as soon as the switch moves off-normal and is de-energized at the end of the group selecting movement to initiate the hunting movement, the test relay being de-energized when an idle line is 55 found and again completing a circuit for the first

relay which thereupon again energizes the test relay and switches the wipers through.

According to a further feature of the invention in an automatic switch arranged to perform a hunting operation the relay which by its de-energization initiates the hunting movement is arranged to be re-operated on the termination of the hunting and when subsequently released initiates the restoration of the switch to normal and guards it against seizure until normal position is reached.

Still another feature of the invention is that in an automatic switch arranged to hunt for an idle line when an idle line is found a relay de-energizes due to the absence of busy potential on 15 the test contact and on releasing applies busy potential to the contact to prevent seizure of the line by a similar hunting switch having access thereto.

If the switch is arranged for the known system in which earth is employed to indicate the engaged condition and the absence of earth indicates that a line is free, the invention offers the additional advantage that if a test contact should have booster battery connected to it owing to a 20 metering operation taking place at that instant, this will have the same effect as the normal busy earth and there is no danger of the switch seizing the line or operating improperly. Furthermore a high resistance earth which might not permit the 25 operation of a relay is sufficient to maintain it operated so that the switch will not seize a line thus marked.

The invention will be better understood from the following description of one method of carrying it into effect which should be taken in conjunction with the accompanying drawings, Figs. 1 and 2. These are diagrammatic circuit drawings and show the invention applied to a vertical and rotary switch of the mechanical construction 35 disclosed in Patent No. 2,028,689, granted Jan. 21, 1936, which switch is arranged to have two sets of wipers each having access to 100 outlets. The operation of the switch is that in response to the controlling train of impulses the wipers are 40 stepped vertically and then perform a rotary hunting movement. Release is effected by re-energizing the rotary magnet whereupon the switch advances to the end of the bank, drops clear and then rotates back to normal under 45 spring tension.

Referring now to the drawings, when the switch is taken into use a loop is placed across the negative and positive conductors, which operates relay A and in turn relay B. If the switch is function- 50 55

- ing as a first selector, the earth to the lower winding of relay A may be supplied by way of a dial tone transformer, in order that the calling subscriber may be informed when the circuit is in readiness to respond to the dialled impulses. Relay B upon operating, at armature *b1* connects earth to the release trunk conductor P to guard the switch and at armature *b2* operates relay C over its lower winding which is of high resistance. Relays B and C together prepare a number of circuits the effect of which will be appreciated subsequently, but no further change takes place due to the seizure of the switch.
- Upon the reception of the setting impulses, relay A responds and repeats them by way of armature *a1* to the vertical magnet VM in series with the upper low resistance winding of relay C and accordingly the wipers are raised to the desired level. As soon as the wipers leave the normal position, the off-normal springs are mechanically operated, thereby at springs N2 extending earth from release trunk conductor P to operate relays HA and HB over their right-hand windings. These relays at armatures *ha4* and *hb4* short-circuit the lower winding of relay C but it will be understood that this relay remains operated during impulsive owing to the intermittent energization of its upper winding in circuit with the vertical magnet and the slugging effect of its short-circuited winding. Relay B similarly remains operated by reason of the copper slug surrounding its core.
- At the end of the train of impulses relay A remains operated and after a short period relay C releases and at armature *c3* connects the righthand winding of relay HB to the test wiper *P1*. The righthand winding of relay HA is already connected to the test wiper *P2* over its own armature *ha3* and the armature *hb3*. Moreover, at armature *c4* a circuit is completed for the rotary magnet RM in series with its interrupter contacts *rm* to earth on the release trunk conductor P, so that the wipers are advanced into engagement with the first set of contacts in the level selected. Rotary off-normal springs NR1 to NR4 are mechanically operated as soon as the wipers commence to rotate and disconnect various circuits which are no longer required after the commencement of the rotary movement.
- If both outlets now engaged are busy, relays HA and HB will be maintained by earth picked up by the test wipers after the circuit to their lefthand windings is disconnected by the opening of the interrupter contacts *rm*. Accordingly after the rotary magnet releases due to the opening of the interrupter contacts and these contacts therefore close, the magnet is again energized to advance the wipers on to the second set of contacts. It will be noticed that while the wipers are moving from contact to contact relays HA and HB are held over their lefthand windings in parallel with the rotary magnet. This stepping operation continues automatically until an idle line is found, or alternatively the wipers are advanced to the 11th position.
- If wiper *P2* is the first to encounter a free outlet, relay HA will restore when the interrupter contacts open, and at armature *ha1* cuts the drive circuit to the rotary magnet to prevent further movement of the wipers, and at armature *ha3* extends earth to wiper *P2* and the test contact to immediately busy the outlet selected. Relay HB however remains held from the earth encountered by wiper *P1*, and as soon as relay HA is released an alternative holding circuit is

provided to the centre winding of relay HB to maintain it operated.

It will be remembered that while relays HA and HB were both operated, the lower winding of relay C was short-circuited, but when relay HA de-energizes the short-circuit is removed and relay C re-operates, thereupon switching the speaking leads through to the lower set of wipers. Relay A is now disconnected since the rotary off normal contacts NR3 and NR4 have opened and on releasing it opens the circuit of relay B. Shortly afterwards therefore, relay B releases but relay HB remains operated by earth on the release trunk conductor which has been extended back from the succeeding switch over the *P2* wiper. Relay C also remains operated after the release of relay B by the energization of its lower winding over the operated armature *hb4* and the resting armature *ha4*.

If however, the *P1* wiper is the first to encounter a free outlet, relay HB immediately releases to guard the outlet selected, and disconnects the driving circuit for the rotary magnet. Relay HB also releases relay HA but upon the operation of relay C as described above relay HA is re-operated over its middle winding and accordingly switches the connection through to the upper set of wipers.

In case both test wipers encounter free outlets simultaneously, both testing relays HA and HB restore, whereupon relay C energizes and re-operates relay HA to switch the connection through over the upper set of wipers. In these circumstances, therefore, it is clear that priority will always be given to the upper set of wipers.

If all outlets in the level selected prove busy, the wipers are rotated to the 11th position where cam springs *S1* to *S3* are mechanically operated, thereby at springs *S1* releasing relay HB and connecting earth to the test wiper *P1* to operate the overflow meter not shown, but assumed to be connected to conductor *10*. Relay HB on releasing brings down relay HA but when relay C operates it re-operates relay HA to switch the upper set of wipers through to the 11th step contacts which are multiplied together and connect with the windings of relay A. Furthermore, at cam springs *S2* busy flash and tone from the cam assembly *BT* is extended through the lower winding to relay A and the 11th contact, wiper *1* to the positive line to inform the calling subscriber that the connection is unavailable. During the flash period relay A is released, but owing to the closure of cam springs *S3* relay B is held over its lefthand winding by battery supplied from the cam assembly *BH*.

Upon the release of the connection at the end of the conversation, earth is removed from the release trunk conductor P and relay HA or relay HB, as the case may be released. This opens the circuit for relay C which de-energizes in its turn, and at armature *c4* completes a self-interrupted driving circuit for the rotary magnet RM to the common conductor *11* extending to release alarm equipment. Accordingly the wipers are rotated clear of the banks, after which they fall and then rotate below the banks under spring tension back to their normal position, where the off normal springs *N1* open the homing circuit. Preferably during the vertical release movement of the wipers, the rotary magnet is mechanically prevented from opening its interrupter contacts, so that there is no tendency for it to chatter. The armature *b6* provided in the circuit of relay

A ensures non-interference with the selector during release.

During the release period the switch is guarded by the application of earth to the release trunk 5 conductor P over armature c¹ and off normal springs N², but it will be noted that at the commencement of release an initial unguard is provided to enable preceding switches to restore, this period being represented by the sum of the 10 release time of relay HA or relay HB and that of relay C. It is found that this time may be adjusted with some degree of accuracy and therefore the unguard during release may be regarded as substantially constant and is conveniently of 15 the order of 25 milliseconds.

In case for any reason the switch fails to restore, the off normal springs N¹ remain closed, and as a result of the prolonged connection of battery to conductor 11, the release alarm equipment 20 functions after a delay period and provides an indication of the faulty condition.

It should be mentioned that at armature hb5 a circuit is prepared to the common conductor 12 extending to a test buzzer, which may be operated 25 by short circuiting the test jack springs T². This enables the set of wipers in use to be determined without the need for removing the dust cover from the switch and examining the actual relays. The switch as shown is provided with a 30 lamp LP which is lighted in circuit with a common conductor 13 extending to exchange alarm equipment, which provides a signal in case the switch is seized but not operated within a predetermined time.

The terminals marked T¹ to T⁸ in the drawings 35 are assembled in the form of a test jack located at the front of the switch to facilitate testing. The condenser QA and the associated resistance are provided as usual in the magnet circuits for 40 spark quenching purposes.

According to the invention therefore, an improved group selector switch has been designed in which by arranging for the test relays to de-energize when an idle line is encountered, the unguarded interval has been almost completely 45 eliminated and moreover the switch operates satisfactorily if it encounters a high resistance earth or booster battery which serves as a definite busy indication. A further advantage is that there is 50 definite priority of switching without any complicated sets of contacts which require very careful adjustment.

We claim:

1. In a selector switch, a driving magnet, a 55 circuit for operating said magnet to advance the switch wipers in search of an idle trunk, a test relay maintained energized over the test contacts of busy trunks and deenergized only when an idle trunk is reached, contacts on said relay for holding the circuit of the driving magnet closed while the relay is energized and for opening it to stop the switch when the relay deenergizes, and contacts on said relay closed by the de-energization thereof for placing a busy potential 60 on the test contact of the selected trunk.

65 2. In a selector switch having two sets of wip-

ers, each set including a test wiper, means for operating said switch to search for an idle trunk with both sets of wipers, two test relays held energized over the two test wipers, respectively, only so long as busy trunks are encountered, and contacts on each test relay for stopping the switch and for placing a busy potential on its associated test wiper when such wiper finds an idle trunk. 5

3. In a selector switch having two sets of wipers, each set including two talking circuit wipers 10 and a test wiper, means for operating the switch to search for an idle trunk with both sets of wipers, two test relays held energized over the two test wipers, respectively, so long as said wipers encounter busy trunks, contacts on each test relay for stopping the switch when the relay de-energizes responsive to its associated test wiper finding an idle trunk, and means effective when any test wiper finds an idle trunk for completing talking circuit connections to the associated talking circuit wipers, said connections including contacts of the deenergized test relay and also contacts of the other test relay in energized condition. 15

4. In a selector switch, means for operating 20 said switch to search for an idle trunk, a test relay deenergized to stop the switch when an idle trunk is found, means for reoperating said relay to connect up the talking circuit wipers of the switch, and means for preventing the reoperation 25 of said relay from restarting the switch.

5. In a selector switch, two sets of wipers, each 30 set including talking circuit wipers and a test wiper, two test relays controlled over the two test wipers, respectively, and contacts on each test relay effective when the relay is energized to connect up the talking circuit wipers of the set whose test wiper is associated with the other test relay. 35

6. In a selector switch having primary and secondary movements, a combined changeover and 40 switching relay, means for energizing said relay during the primary movement and for deenergizing it at the end of the primary movement to start the secondary movement, and means for energizing said relay at the end of the secondary 45 movement to close the talking circuit through to the wipers of the switch.

7. In a two motion selector switch, a line relay, a switching relay for disconnecting the incoming line from said line relay and for extending the line through to the switch wipers upon the completion of the operation of the switch, means for utilizing said switching relay as a changeover relay, and secondary off-normal contacts for preventing the energization of said switching relay when used as a changeover relay 50 from disconnecting said line relay. 55

8. In a selector switch of the searching type, two sets of wipers, a switching relay common to both wiper sets, two test relays, a circuit for said switching relay, and contacts on said test relays for maintaining said switching relay short circuited to prevent its energization while the selector is searching for an idle trunk. 60
